UNITED STATES PATENT OFFICE.

JOSEPH NIELANDER, OF STERLING, ILLINOIS, ASSIGNOR OF ONE-HALF TO
FRED MACKE, OF KOKOMO, INDIANA.

COMBINATION-PADLOCK.

SPECIFICATION forming part of Letters Patent No. 718,146, dated January 13, 1903.

Application filed December 21, 1901. Serial No. 86,835. (No model.)

To all whom it may concern:

Be it known that I, JOSEPH NIELANDER, a citizen of the United States, residing at Sterling, in the county of Whiteside and State of Illinois, have invented a new and useful Combination-Padlock, of which the following is a specification.

This invention relates generally to padlocks, and more particularly to a combination or permutation padlock, the object of the invention being to provide an exceedingly simple, durable, and efficient construction of combination-padlock comprising very few parts in its make up, thereby minimizing the liability of getting out of order.

Another object of the invention is to provide a combination-padlock of such construction that all of the parts will be connected with the lock-case at all times, thereby avoiding the liability of some of the parts becoming misplaced.

The invention consists in certain features of construction and combination hereinafter fully described, and pointed out in the claim.

In the drawings forming part of this specification, Figure 1 is a perspective view illustrating a combination-padlock constructed in accordance with my invention. Fig. 2 is a vertical longitudinal section, the shackle and bolt being shown in elevation. Fig. 3 is a transverse section taken on the line 3 3 of Fig. 2. Fig. 4 is a horizontal section taken on the line 4 4 of Fig. 2. Fig. 5 is a vertical longitudinal sectional view, the shackle and bolt being shown in elevation and also in their unlocked positions. Fig. 6 is a detail transverse section taken on the line 6 6 of Fig. 5. Fig. 7 is a detail perspective view of one of the tumbler-disks, and Fig. 8 is a detail perspective view of a locking-bolt.

In the practical embodiment of my invention I employ a case A, which is preferably made in the form of a block of metal having a circular bore A' adjacent to one end passing entirely through the said block or case, and a socket A², produced in the upper side of the block or case adjacent to the opposite end. The case is also formed with a central opening A³ for the purpose of receiving the tumbler-disks, hereinafter described, and the case is also constructed with a transverse or hori-

zontal bore D⁴, which passes through one side of the case and communicates with the central opening and also with the vertical bore A'.

The shackle B comprises the longer member B' and the shorter member B², the member B' being arranged in the bore A', while the end of the member B' is adapted to rest in the socket A² when the shackle is locked. The member B' is arranged to slide vertically within the bore A', so as to clear the member B² from the socket A², and after the said member has been lifted out of the socket the shackle is rotated to fully expose the free end of the shackle. A stock-pin B³ is fixed in the lower end of the member B' to prevent the said shackle being withdrawn from the case, and the bore is slightly enlarged at its lower end, as shown at A⁵, to permit the movements of the said pin. The lower end of the bore is closed by means of a plug A⁶, secured in any suitable manner. A locking-bolt C is arranged to slide in the transverse or horizontal bore A⁴, and arranged upon the bolt within the case are the tumbler-disks D, said tumbler-disks being preferably circular in form and having marks and numerals D' produced upon their peripheries for the purpose of guiding the operator in the manipulation of the lock. The bolt C is provided with a series of bits C', and the tumbler-disks are each provided with a radial ward-notch D², which permits the free passage of the bit therethrough, and consequently permits the longitudinal movement of the bolt C within the case and through the tumblers when the said ward-notches are brought into alignment with each other and with the bits of the bolt, as most clearly shown in Fig. 6. One face of each disk is cut away or recessed, as shown at D³, to receive the bit, thereby enabling the said disks being arranged in close contact with each other. The member B' of the shackle has a recess or notch B⁴ produced therein, said recess or notch being adapted to receive the end C² of the bolt, and inasmuch as this end is shaped in the form of a double bevel the notch B⁴ is usually constructed in the form of a V, the purpose of such constructions being made apparent hereinafter. A retaining-screw C³ passes through the bottom of the socket A² down into the bore A⁴ after

the bolt has been put in place, the purpose of said screw being to prevent the withdrawal of the bolt C.

In operation the tumbler-disks are moved around until all of the ward-notches are brought into alignment with each other and with the bits upon the bolt. The shackle after being passed through the hasp or staple to be fastened is forced into the case so that the end B² will fit into the socket A². The notch B⁴ is thereby brought directly opposite the end of the transverse bore A⁴, and the bolt is projected inwardly by pressing upon its outer end, thereby forcing the end C² into the notch or recess B⁴. The tumbler-disks are then turned in either direction, so as to throw the ward-notch out of register, and the locking operation is complete. When it is desired to open the lock, the disks are brought around to the proper combination, thereby driving the ward-notches into alignment with the bits upon the bolt, and by pulling upon the shackle the member B' slides within the bore A', and the inclined side of the recess B⁴, working upon the beveled end of the bolt C, forces said bolt outwardly, as most clearly shown in Fig. 5, thereby permitting the shackle to move upwardly, entirely lifting the end B² out of the socket A², and as soon as the said end is clear of its socket the shackle can be rotated upon the member B', thereby completely opening the lock.

It will thus be seen that I provide an exceedingly simple construction of combination-lock and one which owing to its simplicity is not liable to get out of order.

Having thus fully described my invention, what I claim as new, and desire to secure by Letters Patent, is—

In a lock of the kind described, the combination with a casing comprising a solid piece

having vertical bores therein, one of which is shallow and the other extending entirely through the casing, being enlarged near its lower end and closed by a plug, a longitudinal bore communicating with said second bore, and a recess or cut-out portion in the middle of said casing, said recess being in communication with said longitudinal bore; of a shackle having one long leg and a shorter one, the longer leg being located in the deeper bore and having a notch or V-shaped depression in its inner side and a pin or lug near its end abutting against the shoulder formed at the juncture of the bore and the broadened or large bore at its end, thereby allowing said leg a limited vertical movement in addition to its rotary movement and the shorter leg entering and leaving said shallow bore, as said longer leg is either in its lower or upper vertical position, a locking-bolt contained in said longitudinal bore, having a limited sliding longitudinal movement therein, a pin passing through the bottom of said shallow bore into said longitudinal bore and limiting the movement of said bolt, a double bevel in the inner end of said bolt engaging the notch in said shackle-leg when the same is in its lowest position, and bits or lugs on said bolt, and tumbler-disks mounted in said central recess, upon said bolt and having radial ward-notches therein, allowing said bits to pass through and the bolt to disengage said shackle when the notches are in alignment, said tumblers being cut out on the side to accommodate said bits when they are not in the said notches, substantially as described.

JOSEPH NIELANDER.
